UNITED STATES PATENT OFFICE

130,124

DESIGN FOR A RALLY STICK

Edward Hart, Portland, Oreg.

Application August 7, 1940, Serial No. 94,288

Term of patent 7 years

To all whom it may concern:

Be it known that I, Edward Hart, a citizen of the United States of America, residing at Portland, county of Multnomah, and State of Oregon, have invented a new, original, and ornamental Design for a Rally Stick, of which the following is a specification, reference being had to the accompanying drawing, forming a part thereof, wherein:

I claim:

The ornamental design for a rally stick, as shown.

EDWARD HART.
